UNITED STATES PATENT OFFICE.

ISAAC POMEROY, OF NEWARK, NEW JERSEY.

BOTTLE-TOP.

SPECIFICATION forming part of Letters Patent No. 378,108, dated February 21, 1888.

Application filed April 15, 1887. Serial No. 234,869. (No model.)

To all whom it may concern:

Be it known that I, ISAAC POMEROY, of Newark, in the county of Essex and State of New Jersey, have invented a certain new and useful Improvement in Bottle-Tops, of which the following is a specification.

My improved bottle-top is intended more especially for mucilage and analogous semi-fluids, as blacking. I will describe it as used for mucilage in applying the same to papers and other objects in a thin coating from time to time, as required. I employ a brush and a sponge combined as means for applying the mucilage. These are held by peculiarly sewing upon a perforated block or cap of wood which matches the top of the bottle, and is firmly confined thereon by a shell of metal, which latter is screw-formed and engages with a screw-thread on the exterior of the bottle-neck. Its upper portion is slightly coned, with its extreme upper edge flared or coned in the reverse direction. This form promotes the tight fitting of the removable cap, and also aids in returning the unused mucilage from the sponge and brush to the bottle after each operation. There is an offset or internal shoulder in the metal shell at the junction of the screw-threaded with the conical portion, which matching upon a corresponding flange on the wood confines the latter very firmly to the bottle by simply screwing down the shell with sufficient force.

The accompanying drawings form a part of this specification, and represent what I consider the best means of carrying out the invention.

Figure 1 is an elevation of the bottle and top, showing the condition when not in use. Fig. 2 is a corresponding view with the cap removed. Fig. 3 is a central vertical section. The remaining figures show portions. Fig. 4 is a vertical section of the bottle-top at right angles to Fig. 3. Fig. 5 is a corresponding section of the block detached. Fig. 6 is a plan view of the same. Figs. 7 and 8 show modifications. They are sections corresponding to Fig. 4, but at right angles thereto. Fig. 7 shows the bristles extending through the sponge, and Fig. 8 shows a form in which the bristles are omitted.

Similar letters of reference indicate corre-

sponding parts in all the figures where they occur.

A is the upper portion of the bottle, additional marks, as A', being employed when necessary to indicate special parts. A' is a screw-thread formed on the exterior of the mouth, and A² is a collar immediately below it.

B is a foundation cap or block of wood formed with a flange, B', a conical body, B², and a central extension, B³.

C is a bunch of bristles, which project at the top and serve to stiffen and support the sponge D, which latter receives the mucilage through a series of holes, b, and applies it on papers or other objects when the bottle is inverted and properly manipulated. The bristles forming the brush C are folded at the lower end and tightly bound together by a twine, c. The brush is secured by a stout thread, m, inserted through transverse holes, the ends being wound around in a groove, b', and secured by tying or cementing, or both. There are corresponding transverse holes at the higher level represented. These receive threads p, which engage with the sponge D and hold it firmly.

E is a shell of metal, certain portions being designated, when necessary, by additional marks, as E'. The lower portion, E', is screw-threaded. Above this is a shoulder or offset, E², which rests firmly on the flange B' of the wooden block B. Above this the portion E³ is coned, and applies partly against the correspondingly-formed body B² and partly around the piece of sponge D. The upper edge, E⁴, is flared outward sufficiently to aid materially in preventing the surplus mucilage from flowing down outside; but care must be taken not to flare this portion out so far as to interfere with the application of the metal cap G, which performs the essential function of preventing the mucilage from evaporating and hardening in and about the top. The lower edge of the cap G applies tightly upon the tapered surface E³.

The wooden block should have the diameter of its flanged base B' carefully adjusted to the diameter of the interior of the screw-threaded portion E' of the shell, so that it will require some force to insert it. It is preferably inserted by engaging a forked tool in its perforations b and turning it around at the same

time that it is pressed inward, so that the screw-threads will favor its entering. The screw-threads terminate a little below the offset E^2 , preserving a short unthreaded space 5 of a diameter larger than the smallest contracted portion between the screw-threads. It follows that when the wooden block B has been forced fully up to its place in the shell, so that it is held loosely therein, and with the upper 10 surface of its flange B' receiving a sufficient pressure from the under face of the offset E^2 , it may adjust itself nicely to the upper edge of the bottle. The metal shell being turned, forcibly presses its shoulder E^2 down upon the 15 flange B' and holds it tightly.

One advantage due to the close fitting of the parts is that the block B and shell E remain engaged when they are temporarily removed from the bottle for supplying with mucilage, 20 or for any other purpose.

The sponge D may be selected of or may be wrought into the form represented in a single piece; or it may be made up of two or more pieces strongly secured by the threads p . The 25 portion of the sponge which covers the brush may become worn by use, so as to let the end of the brush apply directly in the use of the device; or the parts may be made and matched together, with the brush extending quite 30 through the sponge in the first instance, if preferred in any case.

A portion of the mucilage to supply the device may flow through the brush; but ordinarily the mucilage will flow mainly through 35 the holes b . The surplus which may be received by the sponge and brush will be returned through these passages to the interior of the bottle after each use. The flaring upper edge, E^4 , of the metal shell E facilitates 40 this by arresting and retaining the mucilage which may commence to flow down on the outside of the sponge. The top B^3 , being smaller than the body B^2 , allows the sponge to extend down around the top and be securely fastened with any required degree of firmness 45 without compressing or in any wise affecting the material of the brush. I attach importance to this feature of the device, as also to the passages formed by the holes b separate and 50 distinct from those for the brush, which allow the mucilage to flow down and fill the sponge and brush when the device is reversed.

Modifications may be made in the forms and proportions without departing from the principle or sacrificing the advantages of the invention. I can increase or diminish the num-

ber of holes b and of the transverse threads m and p , which confine the brush and the sponge. The extent to which the central portion, B^3 , of the block B projects upward may vary. It 60 may be suppressed entirely, suitable provisions being made for holding the sponge by threads or other fastenings properly arranged, as the brush C, extending up into the sponge, affords a reliable support for the latter against 65 all ordinary lateral forces.

The support afforded by the brush is preferable to any which can be afforded by a rigid body alone, because of the elasticity of the bristles, allowing the whole to yield, but 70 promptly returning all to the approximately-central position on the bottle-top so soon as the use of the device is completed.

I claim as my invention—

1. In a bottle or holder for mucilage and 75 analogous fluids, the combination, with the bottle or vessel A, of a block, B, having holes b independent of the holes for the brush, and of a brush, C, and sponge D, arranged for joint operation, as herein specified.

2. In a bottle or holder for mucilage and analogous fluids, the block B, having a top, B^3 , smaller than the body B^2 , the brush C and its fastening means m , and the sponge D and its 80 fastening means p , all combined and arranged 85 to serve relatively to each other and to a bottle, A, as herein specified.

3. In a bottle for mucilage, the block B, having a flange, B' , body B^2 , and smaller top, B^3 , the brush C and sponge D and their fastening 90 means m p , the block B being provided with holes b , distinct from those which receive the brush material, and the several parts are combined substantially as herein specified.

4. The brush C and holding means m , in combination with the sponge D and its confining means p , and with the block B, metal shell E, and cap G, as herein specified.

5. In a bottle-top, the block B and separate metal shell E, the latter flared at its top, as 100 shown by E^4 , combined with each other and with the sponge D, bottle A A', and cap G, substantially as herein specified.

In testimony whereof I have hereunto set my hand, at New York city, this 12th day of April, 105 1887, in the presence of two subscribing witnesses.

ISAAC POMEROY.
